UNITED STATES PATENT OFFICE.

LOUIS W. DOWNES, OF PROVIDENCE, RHODE ISLAND, ASSIGNOR TO D & W. FUSE CO., OF PROVIDENCE, RHODE ISLAND, A CORPORATION OF RHODE ISLAND.

ELECTRIC FUSE.

No. 909,564.

Specification of Letters Patent.

Patented Jan. 12, 1909.

Application filed December 15, 1903. Serial No. 185,271.

To all whom it may concern:

Be it known that I, Louis W. Downes, of Providence, Rhode Island, have invented a new and useful Electric Fuse, which invention is fully set forth in the following specification.

My invention relates to inclosed fuses of the plug type, the object being to provide means for indicating the condition of the fuse, said means being so located as to be visible without the necessity of removing the fuse from its socket or base, or of removing a part or parts of the fuse.

To that end the indicating means, such as hereinafter described, are associated with the cover which closes the open end of the cup-like or hollow plug-like inclosing casing and which cover is exposed when the plug fuse is inserted in its socket or base, the indicating means being thus visible even when the fuse is in its socket.

My invention will be more fully explained and completely understood in connection with the accompanying drawings, wherein—

Figures 1 and 2 are sectional views at right-angles to each other, of one embodiment of the invention; Figs. 3 and 4 are detail views of parts of the same; Fig. 5 is a sectional view and Fig. 6 a detail of another embodiment; Fig. 7 is a detail of a label; Figs. 8 and 9 are sectional views of still other embodiments.

Referring to Figs. 1 and 2, 1 is a cup-like or hollow plug casing, preferably of porcelain, surrounded at its lower end by a shell 2, preferably of spun brass rolled to form a screw-thread on its exterior; shell 2 constitutes one of the socket-contacts on the plug casing.

4 is the other socket-contact or terminal on the casing consisting of a headed bolt or pin, the shank of which passes through the end wall of part 1. When the plug fuse is screwed into a socket or base the contacts or terminals 2 and 4 engage corresponding circuit terminals in the socket, in a well-known manner.

5 is the main fuse wire or link connected at its lower end to contact 4 and at its upper end to a conductor 10, shown in the form of a flat strip, which is led downwardly through passage 9 in casing 1, and is electrically connected to shell 2. The fuse link may (or may not) traverse an air space in

the manner set forth in my Patent No. 569,373, October 13, 1896. As illustrated herein an air space 6 is formed by a capsule strung upon the fuse-link. The cavity within the plug casing is filled by the usual non-conducting porous filling 8.

The open end of the cup-like casing 1 is closed by a cover consisting in this instance of a disk 11, of non-conducting material, preferably fibrous. Over cover 11 I place a transparent disk 16 of mica, for example. Both the cover and disk 16 are securely held in place by a spun metal cap 3, open at its center and screw-threaded onto part 1.

7 is an auxiliary or indicator fuse-link or wire, preferably of German silver and of greater electrical resistance than fuse-link 5, electrically connected at one end to contact 4. The indicator wire 7 passes upwardly through filling 8, outwardly through opening 19 in disk 11, and downwardly through an opening 36 in said disk formed by punching out of the same a plug or pellet 12 (Fig. 3). The opening 36 thus formed is large enough to permit the upper end of the indicator wire to be electrically connected, as by solder, to the conductor 10 at point 18.

When this is effected the plug or pellet 12 is forced back into the opening 36 and glued or cemented therein to securely close the opening. The part of the indicator wire which extends along the disk 11, passes over a counter-sunk recess or depression 14 therein; 17 is a small body of material located in recess 14 and about the indicator wire 7. Said material is adapted to be sufficiently heated upon fusing of the indicator wire to afford at the exterior of the cover the desired indication of the blowing of the fuse, preferably by discoloring, charring or blackening a label, such as hereinafter described, due to the heat developed by the burning of said material. I preferably employ a paste composition of ordinary gun-powder dissolved in a water solution of guin-arabic. I may however, employ a material, which, in the absence of a label, will give the desired indication by change of appearance—discoloration, charring or blackening, for example.

Disk 11 may or may not be provided with vent openings 13. The embodiment of the invention shown in Figs. 5 and 6 is similar to that of Figs. 1—4, except for the following differences: The open end of the cup-like casing is closed

2 by a cover consisting of disks 20 and 22. Disk 20 has an opening 30 therethrough and a notch or recess 21 in its edge. The indicator fuse-wire is faced upwardly through opening 30 and extends along the surface of disk 20 to the recess 21 in which it is electrically connected to the conductor strip 10. The second disk 22 placed over disk 20 has a perforation at its center over that portion 10 or the indicator wire 7 which extends along the surface of disk 20; said perforation is lined with a material 24, similar to the material 17 already described, which makes contact with the wire 7. Mica disk 23 may be 15 placed over disk 22, the three disks 20, 22 and 23 being held in place by cap 3. The disks 20 and 22 are preferably hard fibrous material.

The operation is as follows: Upon melting of the main fuse link 5 by excess of current, a certain amount of current passes through indicator wire 7, heating the same to a melting point. The heat thus developed is sufficient to heat or ignite the gun-powder composition (17, Figs. 1-4 and 8, or 24, Figs. 5 and 9), effecting a change in the appearance of the plug fuse at this point in the manner above indicated, and thereby affording at the exterior of the cover what 25 may be designated a "spot-indication" of the condition of the main fuse-wire.

The disk of mica 16, Figs. 1, 2 and 8, or 35 23, Figs. 5 and 9 constitutes an outer exposed transparent covering over the gunpowder composition (or over the paper label 31 which covers said composition, when such label is used) through which the indicated condition of the fuse may be observed at a glance. This covering adds to the safety 40 of the device, as any slight flash or discharge from the gun-powder or other composition 17, or from the burning of the label 31 over said composition, would be on the underside of said covering or disk, and hence not exposed to the atmosphere or in the least dangerous as a source of fire. As 45 will be appreciated, in certain localities the slightest flash or discharge from the fuse would be extremely dangerous. Instead of being made of mica, the disk 16 or 23 may be of any other suitable transparent material sufficiently non-inflammable and non-combustible to withstand the heat generated by the burning of the material 17.

55 31, Fig. 7, is a label, such as above referred to, having imprinted thereon a small circle 32 and adapted to be placed over the gunpowder composition or other material. In Fig. 8, this label is shown as applied to the 60 construction of Figs. 1 to 4, being secured to cover 11 by adhesive material with its central part over the gunpowder composition 17; the mica disk 16 is over the label.

In Fig. 9 the label is applied to the construction of Fig. 5, being secured to disk 22

by adhesive material with its central part over the gun-powder composition 24, and covered by mica disk 23. Upon heating of the gun-powder composition the desired indication is afforded by the production of a 70 discolored, charred, or blackened spot on the label,—or in some cases incidentally burning a hole in the label,—at or within the circle 32. The arrangement may be such as to develop sufficient heat to actually burn a hole 75 through (at the same time discoloring or blackening) the label, but I prefer to avoid all flame and to simply char, blacken or discolor the label.

From the above description it will be understood that I provide at the exposed or outer end or part of the inclosed plug fuse (meaning thereby that part which is not obscured from view when the plug fuse is inserted in a socket) means for giving a visual 85 indication of the condition of the fuse.

As is apparent from the several embodiments shown, my invention is capable of various mechanical expressions and is not restricted to details of construction. 90

What I claim is:

1. In a plug-fuse, a cup-like or hollow plug casing; a main fuse-wire inclosed by the casing; a cover closing the open end of the casing; an auxiliary or indicator fuse-wire also inclosed by said casing and in parallel circuit with the main fuse-wire, said indicator wire being associated with said cover and adapted to afford at the exterior of the cover a visual indication of the condition of said main fuse-wire; and an annular cap removably securing the cover on the casing. 95

2. In a plug-fuse, a cup-like or hollow plug casing; a main fuse-wire inclosed by the casing; a cover closing the open end of the casing; indicating means including an auxiliary or indicator fuse-wire in parallel circuit with the main fuse-wire, and a small body of suitable combustible material associated with the cover and indicator wire and adapted upon fusing of said indicator wire to afford at the exterior of the cover a visual indication of the condition of the main fuse-wire; and an outer transparent suitably non-combustible covering applied to the cover over the indicating means. 110

3. In an inclosed electric fuse of plug type, a casing comprising a hollow member and two disks closing the outer open end thereof; a main fuse-link within the casing; and an auxiliary or indicating fuse-link or wire within the casing having a part passing between the disks. 115

4. In an inclosed electric fuse of plug type, a casing comprising a hollow member and two disks closing the outer open end thereof, the outer disk having an opening therein; a main fuse-link within the casing; an auxiliary or indicating fuse-link or wire within 120

the casing and having a part passing between the disks and under the opening in the outer disk; and a material in said opening and in contact with the auxiliary fuse-link and adapted upon disruption of the main fuse-link to be heated by the auxiliary fuse-link to effect a visual indication of said disruption.

5. In an inclosed electric fuse of plug type, 10 a casing comprising a hollow member and two disks closing the outer open end thereof, the outer disk having an opening therein; a main fuse-link within the casing; an auxiliary or indicating fuse-link or wire within 15 the casing and having a part passing between the disks and under the opening in the outer disk; and a material in said opening and in contact with the auxiliary fuse-link and adapted upon disruption of the 20 main fuse-link to be heated by the auxiliary fuse-link to effect a visual indication of said

disruption; and an outermost transparent disk or covering through which said indication is visible.

6. A plug fuse having a hollow base open 25 at one end, metallic contacts thereon, main and indicator wires connecting said contacts, an insulating disk over the open end of said base and provided with apertures through which the indicator wire is threaded, a disk 30 of transparent material located outside said insulating disk, and a centrally apertured cap engaging the sides of said base and clamping the said disks between its inner surface and the end of the base. 35

In testimony whereof I have signed this specification in the presence of two subscribing witnesses.
